J. S. RONEY

DRYING DEVICE

Filed March 24, 1924

Fig. 1.

Fig. 2.

Patented Nov. 24, 1925.

UNITED STATES PATENT OFFICE.

JOHN S. RONEY, OF MIDDLETOWN, OHIO.

DRYING DEVICE.

Application filed March 24, 1924. Serial No. 701,544.

To all whom it may concern:

Be it known that I, JOHN S. RONEY, a citizen of the United States, and resident of Middletown, in the county of Butler and State of Ohio, have invented certain new and useful Improvements in Drying Devices, of which the following is a specification.

My invention relates to devices for drying damp articles, such as laundry work, clothing, lumber, paper, etc., by means of a forced draft or drafts of heated air, or gas, and my purpose is to provide a device of this kind that is of simple, comparatively inexpensive construction, and that is rapid, safe and thoroughly reliable and efficient in operation.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the separate views

Figure 1 is a vertical section through a drying device embodying the novel and essential features of my invention, said section being taken approximately on the line 1—1 of Fig. 2; and

Figure 2, a horizontal section taken approximately on the line 2—2 of Fig. 1.

The device of my invention which consists essentially of a receptacle to receive articles to be dried and means for forcing heated air or gas therethrough thereby to dry articles contained therein may be formed from any desired material into any desired size and shape, but for the sake of convenience is shown in the present instance as formed from sheet metal and of rectangular shape, in which embodiment it is composed of a base 10, a cooling device or devices 11 rising from said base and enclosing one or more sides of the receptacle, a hinged door 12 providing a closure for one side of the receptacle, and a top 13, the device being comparatively air-tight when closed.

Base 10 is in the form of a pen having upstanding side walls 14 terminating at their upper ends in turned flanges 15 on which the bottoms of the cooling device or devices 11 rest, whereby said cooling de-

vice or devices are supported above the bottom wall of the base, and the dome-like top 13 is secured to the upper ends of the cooling device or devices whereby the device as a whole is made rigid, strong, and comparatively airtight.

Each cooling device 11 consists of a cooling jacket 16 surrounding a vertical space 18 which space communicates at its lower end with the interior of the base 10 and at its upper end with the interior of the receptacle, cooling water or other fluid being supplied to and removed from said jacket in any preferred manner as by means of pipes 17.

Between the cooling device or devices 11 and the receptacle proper is a lining 19 of sheet metal or other suitable material, which lining is open at its top where it is provided with outwardly directed flanges 20 resting on the upper end of the cooling device or devices and at its bottom is closed as at 21 and extends into the interior of the base 10. It also is open at its front where it is provided with flanges 22 secured against the forward edges of the cooling device or devices and by means of the flanges 20, 22 its side walls are maintained spaced from the inner walls of the cooling device or devices as shown.

In the bottom wall 21 of lining 19 is an opening or openings 23 arranged to admit air or gas from the interior of the base 10, and a fan or fans 24 of any suitable type is or are provided to force air or gas through said opening or openings into and through the receptacle, while within the receptacle, slightly above the bottom wall of lining 19, is a screen 25 of wire mesh or other suitable foraminous material adapted to direct the forced air or gas currents prior to the same entering the receptacle in such a manner as to prevent dead spaces in the receptacle.

Within the base 10 is one or more heaters 26 of any suitable type adapted to heat the air or gas before it is forced through the screen deflector to the receptacle by said fan or fans, whereby heated air or gas is supplied to the receptacle for drying articles contained therein, said heaters preferably being located below the fans whereby the air or gas is treated before it passes through the fan or fans.

Any suitable means such as brackets or the hangers indicated generally at 27 may be provided within the receptacle to sup-

port articles therein to be dried, and as indicated by dotted lines at 28 in Figure 1 of the drawings a partition or partitions may be provided to divide the receptacle into compartments whereby certain articles to be dried may be maintained separate from other articles to be dried.

At the bottoms of the cooling device or devices 11, adjacent to the walls thereof defining the spaces 18, are short extended flanges 29, the purpose of which, is to direct condensate waters forming on the inner walls of the cooling device or devices into troughs 30 disposed beneath the openings 18, said troughs serving to cause such water to flow to a suitable drain (not shown) and the device thus maintained substantially free of moisture.

The method of using my device as well as its mode of operation is apparent and as follows:—The door 12 is opened and the wet or damp articles to be dried are placed within the receptacle on the hangers 27 or otherwise disposed, after which the door is closed and the heaters and fans 26 and 24 are set into operation to respectively heat the air or gas within the base and force it through the receptacle and through the articles contained therein. As the heated air or gas passes through the receptacle it absorbs the moisture from the articles and in a moisture laden condition it passes through the spaces 18 surrounded by the cooling jacket or jackets 16 where it contacts with the relatively cold surfaces of the cooling device or devices and the moisture therein is thus precipitated therefrom. The precipitated moisture collects on and flows downward over the inner surfaces of the spaces 18 and drips from the flanges 29 into the troughs 30, being conveyed away by said troughs as previously indicated. The air or gas now being cooled passes again into the base 10 where it is reheated and again forced by the fans 24 through the receptacle, the operation of drying thus utilizing the same air or gas over and over and being continuous as is apparent.

From the foregoing description considered in connection with the accompanying drawings, it is believed that the construction, operation and advantages of my device will be apparent. It is desired to point out, however, that various changes and desirable additions may be made in and to the structure shown within the spirit and scope of my invention as defined in the appended claims.

I claim:—

1. In a device of the character described, a base, a receptacle above and communicating at its bottom directly with said base, a cooling device at the side of said receptacle having a passage therethrough communicating at its bottom with said base and at its top with said receptacle, heaters arranged within said base, and means also arranged within said base for forcing heated air therefrom through said receptacle.

2. In a device of the character described, a receptacle adapted to receive damp or wet articles to be dried, means for forcing heated air or gas through said receptacle thereby to dry articles contained therein, a cooling device for precipitating moisture from said air or gas, after the same has been forced through said receptacle, means to convey the moisture precipitated from said air or gas to a point of discharge, and flanges on said cooling device or devices to direct moisture precipitated from said air or gas into said conveying means.

3. In a device of the character described, a base, a receptacle above said base adapted to receive articles to be dried, a cooling device at the side of said receptacle having a passage therethrough communicating at its top with said receptacle and at its bottom with said base, means for heating air within said base, means for forcing heated air from said base into said receptacle and through said passage, a trough at the bottom of said passage to receive moisture precipitated from said air during its flow through said passage, and flanges extending downwardly from the sides of said passage towards said trough to direct moisture collecting on and flowing down the sides of said passage into said trough.

4. In a device of the character described, a base, a receptacle above said base adapted to receive articles to be dried, a cooling device at the side of said receptacle having a passage therethrough communicating at its top with said receptacle and at its bottom with said base, the bottom of said base having an opening therein, a fan within said base arranged to force air from the base through said opening into the receptacle and thence through said passage back to the base, and a heater within said base.

In testimony whereof I hereunto affix my signature.

JOHN S. RONEY.
